James Beaumont

Letters Patent dated December 3, 1814.

The Liberator referred to in those Letters will and making
part of the same containing a description in the words of
the late James Thimbleby himself of his mode of
working Cotton Weaving.

The cotton being previously carded in a cotton carding machine whilst in factories called a Breaker is taken from the loops or bats and put through the machine a second time in sufficient quantity and carded on that part of the machine called the drum; the machine is then stopped, it is now ready for a cylinder, which in the common operation of carding is assisted by the friction of the skin in a well wet with a large number of your glue, flour or like property intended to preserve it liquid & well when the size is put on with a sponge which the operator holds in one hand while he gently turns the drum with the other, continuing to press the size from the sponge upon the roller or cylinder until the whole surface of the sheet of cotton is properly sized and when dry the size gives a glutinous texture on the surface of the sheet of cotton. The roller is then taken off and the sheet of cotton removed and from the common practice of the carding machine the sheet of cotton is now ready for the spinning machine.

and the house is now
in the hands of the
new owners. The
old man is still
there, but he is not
the same man as
he was, according
to the neighbors.

Shortly you will receive a copy of all my right to the
above Letter of Credit for making return to us, until

Patentee, Kawoomb of Morton, for the sum of one
hundred dollars which I hereby acknowledge to have
received this thirtieth day of September in the year of
our Lord one thousand and eight hundred and twenty six and
wishes my hand

signed in presence of us

E. B. Lottrop

Thos. D. Lane
